UNITED STATES PATENT OFFICE.

CLAUDE WILLIAM DENNY, OF LONDON, ENGLAND.

ELECTRIC SWITCH.

Application filed June 24, 1922. Serial No. 570,630.

To all whom it may concern:

Be it known that I, CLAUDE WILLIAM DENNY, a subject of the King of Great Britain, and a resident of London, England, 5 have invented certain new and useful Improvements in Electric Switches; and I do hereby declare the following to be a full, clear, and exact description of the same, reference being had to the accompanying drawings, forming part of this specification, and 10 to the characters of reference marked thereon.

This invention relates to electric switches of the knife-blade kind having a quick break 15 action and refers chiefly, though not exclusively, to switches adapted to be placed within the handle of an electrically heated iron or other electrically operated or controlled device or appliance where economy of space 20 is to be considered while maintaining the efficiency of the switch also wherein the opening and closing of the switch is controlled by the act of the user gripping, or releasing his or her grip from the handle of 25 the device.

The Switches controlled by the user by the act of gripping the handle of the device, and which automatically open when the grip is released, are subject to a greater amount 30 of wear than ordinary switches owing to the more frequent operation and as arcing across the contacts will take place every time the switch is opened, ordinary switches, as hitherto constructed will, when so used, soon become erratic and inefficient or useless, furthermore, there is a force, usually a spring, 35 constantly tending to open the switch and this force has to be counteracted or overcome by the grip of the user, so that should the user's fingers tire there is a likelihood of 40 the switch being frequently opened accidentally.

It is the chief object of the present invention to overcome these defects and drawbacks 45 and to provide a switch wherein the pivoted knife-blade member is furnished with a number of separate contacts in series which are adapted to cooperate with a number of contacts in series on the stationary member and wherein a relatively strong 50 spring acts upon the blade member and a relatively weak spring acts upon the operating lever, whereby the pressure required to be exerted by the user is comparatively 55 slight and sufficient only to overcome the

light spring which acts on the handle. Further 60 a locking device is provided to act upon and lock the movable member in the closed position and is adapted to be released by or through the movement of the handle, or operating lever.

In accordance with this invention also the contacts are so contrived and arranged that breaking takes place between them all simultaneously. This is done by sloping or 65 stepping the contacts of either or both series.

Referring to the accompanying drawings:—

Fig. 1 is a sectional elevation of an electric iron in the handle of which the present invention is embodied, the switch being shown in the open position.

Fig. 2 is a sectional elevation of the handle shown in Fig. 1 and showing the switch 75 in the closed position or a position occupied by the parts when firmly gripped by the user as when closing the switch.

Fig. 3 is a sectional elevation also of the handle shown in Fig. 1, but showing the 80 switch controlling lever or handle moved to its fully open position preliminarily to movement of the switch under pressure of its spring.

Fig. 4 is an end section on the line 4—4 of Fig. 1.

Fig. 5 is an end section on the line 5—5 of Fig. 3.

Fig. 6 is an end view of the iron-handle showing the position of the leads and 90

Fig. 7 is a sectional view showing the locking device.

Figs. 6 and 7 are drawn to a larger scale than the other figures.

A is the stationary contact member, B the 95 movable contact blade, C the operating lever or handle, D the spring catch, E the spring acting on the contact blade and F the spring acting upon the operating lever.

The stationary contact-carrying member 100 is conveniently in the form of a bar A disposed in a slot or recess g in the upper side of the handle G and secured to the handle at each end by screws σ . The handle G is furnished with a removable part G^1 secured 105 to the main part of the handle G by a screw g^1 , so that by undoing this screw and removing the part G^1 the member A can be got at for repairs or inspection.

Projecting from the lower side of the bar 110

A and into a recess g^2 in the handle G are two U-shaped contact members A¹ A² and a double U-shaped contact member A³, these contacts being insulated from the bar A in any convenient manner.

The contact carrying blade B is pivoted at b to a post or block K which conveniently is carried by or attached to the underside of the plate A and projects into the recess g^2 .
10 Mounted on the bar B are two contacts B¹ B² which are separate from each other and are insulated from the bar B in any convenient manner.

Two terminal leads J² J³ are brought from the usual heating element within the iron and led through openings in the end of the handle a wire J being led from the lead J² to the contact A¹ and a similar wire J¹ from the lead J³ to the contact A².

20 The spring E controlling the operation of the contact blade B is conveniently in the form of a comparatively strong coil spring one end of which is secured to the lower side of the bar A and the other end fits into a 25 boss on the blade B.

The contact B¹ on the blade B is adapted in the closed position of the switch to form a bridge piece between the contact A¹ and one limb of the contact A³, while the contact 30 B² on the blade B forms a bridge piece between the second limb of the contact A³ and the contact A². As the switch will automatically open and the contacts be broken each time the user releases the grip as when 35 bringing a fresh portion of the work to the iron or when obtaining a fresh piece of work arcing will take place frequently between the contacts and the destructive influence of this arcing, by the present invention, 40 is reduced by causing the arcing to take place at the four points arranged in series.

As the blade B is pivoted and therefore moves through an arc of a circle it is necessary to provide means whereby the contacts 45 will be broken at all points simultaneously. This is accomplished according to the present embodiment of the invention by sloping the stationary contacts A¹ A² A³ so that the contact A³ is longer than the contact A² and the contact A¹ longer than the contact A³.
50 The same effect may be produced by sloping or tapering the contacts B¹, B² or by sloping or stepping the contacts of both series.

The operating lever C is pivoted at c to 55 the block or post K within the recess g^2 in the handle G and is itself adapted in the closed position of the switch, to be accommodated within this recess so that its other portion conforms practically to the shape of 60 the handle G (see Fig. 2). The inner side of the lever C is recessed to accommodate or receive the blade B both in the closed and open positions of the switch (see Figs. 1 and 2).

65 In the recessed part of the lever C is a

block C¹ which acts as a stop piece for the blade B which latter is operated by the spring E and this block presses on the blade B to close the switch when the handle G and lever C are gripped by the user.

70 Acting upon the lever C and constantly tending to push it outward is the spring F one end of which is anchored to a pin on the post K and the other end is secured to a pin on the lever C. This spring is of sufficient strength to move the lever on its pivot when the latter has been released or partially released by the user but is of less power than the spring E acting upon the blade B.

75 In order that the user's hand may not be unnecessarily strained or tired through having to grip hard enough to overcome the power of the spring E and also in order to place the exact point of breaking contact 80 out of the direct control of the user and thus prevent a slow breaking action there is provided the locking device above referred to. This locking device comprises a catch D which is mounted to slide in grooves in the 85 post K and is held in its forward position to engage a nose or shoulder B³ on the blade B by a spring d (see Figs. 1 and 7).

90 At the rear the catch D has two shoulders D¹ which project from the opposite sides of the catch and are adapted to be engaged by the walls of cam slots C² formed on the rear end of the lever C. This catch holds the blade B in the closed position and the lever C can turn on its pivot under the action of the spring F to a limited extent without permitting the cams to withdraw the catch D and release the blade B so that the user need not grip the handle and press the lever C firmly.

95 When the lever C is entirely released from the user's grip the spring F moves the lever C outward to the fullest extent of its movement as in Fig. 3, the cam then withdraws the catch D. The spring E will then move 100 the blade B around its pivot to make a quick break.

105 I claim;—

1. In an electric switch the combination of a stationary member, a pivoted knife-blade member, a number of separate contacts on the stationary member, a number of separate contacts on the knife-blade member the contacts of one member connecting those of the other member in series, an operating lever 115 for the knife-blade member, a relatively weak spring, adapted to act upon the operating lever, and a relatively strong spring adapted to act upon the knife-blade member.

120 2. In an electric switch the combination with a stationary member, a pivoted knife-blade member, and an operating lever for the knife-blade member, of a number of separate contacts on the stationary member, a number of separate contacts on the knife- 125

blade member the contacts of one member adapted to electrically connect the contacts of the companion member in series, a relatively weak spring adapted to act on the operating lever, a relatively strong spring adapted to act on the knife-blade member, and means for locking the knife-blade member in position to close the switch.

3. In an electric switch, the combination 10 with a stationary member, a pivoted knife-blade member, and an operating lever for the knife-blade member, a number of separate contacts on one of the aforesaid members, a number of separate stepped contacts 15 on the other member, the said contacts of both members interconnecting in series upon closing of the knife-blade member, a relatively weak spring adapted to act on the operating lever and a relatively strong spring 20 adapted to act on the knife-blade member.

4. An electric switch comprising a stationary member, a block carried thereby, a knife blade member pivoted to the block, a catch movably carried by the block and releasably engaging the knife blade member 25 to hold it closed, and a lever pivoted on the block for closing the knife blade member and adapted to act upon the catch, upon opening movement of the lever, for rendering the catch inoperative.

5. In an electric switch, the combination 30 with a stationary member, a pivoted knife-blade member and an operating lever for the knife-blade member, of a number of separate contacts in series on one of the members, a number of separate contact members 35 in series on the other member, a relatively strong spring adapted to act on the knife-blade member, a relatively weak spring 40 adapted to act on the operating lever, a slideable catch adapted to act upon the knife-blade member, a spring acting upon the catch, and means on the operating lever for withdrawing the catch from the knife-blade 45 member.

6. In an electric switch the combination 50 with a stationary member, a pivoted knife-blade member, and an operating lever, acting on the knife-blade member, of a number of separate contacts in series on the stationary member, a number of separate contacts 55 arranged stepwise in series on the knife-blade member, a relatively strong spring adapted to act upon the knife-blade member, a relatively weak spring adapted to act upon the operating lever, a slideable catch 60 adapted to act upon the knife-blade member, a spring controlling the catch, and means on the operating lever and interlocking with the catch for withdrawing the catch.

7. In an electric switch the combination 65 of a stationary contact carrying member, a pivoted contact carrying member, an operating lever for the pivoted member, a relatively

strong spring acting upon the pivoted member, a relatively weak spring acting upon the pivoted lever, a catch acting upon the pivoted member and means on the end of the operating lever for actuating the catch. 70

8. In an electric iron, and in combination therewith, a contact carrying member fixed within the handle of the iron, a number of separate contacts in series on the stationary member, leads connected to the terminal 75 contacts of the series, a pivoted knife-blade member working in a recess in the handle, a number of separate contacts in series on the pivoted member, an operating lever recessed to embrace the pivoted member, a 80 relatively strong spring acting on the pivoted member and a relatively weak spring acting on the operating lever.

9. In an electric iron in combination 85 therewith a contact-carrying member fixed within the handle of the iron, a pivoted member adapted to move in an opening in the handle of the iron, a pivoted operating lever, working in the said opening and recessed to embrace the pivoted member, a 90 number of separate contacts in series on the stationary member, leads connected to the terminal contacts of the series, a number of separate contacts in series on the pivoted member, a relatively strong spring 95 acting upon the pivoted member, a relatively weak spring acting upon the pivoted lever and means for locking the pivoted member in position to close the switch.

10. In an electric iron and in combination 100 therewith, a stationary member fixed within an opening in the handle, a pivoted member adapted to move within the opening in the handle, a pivoted operating lever, also working in the said opening, and recessed 105 to embrace the pivoted member, a number of separate contacts in series upon one member, a number of separate contacts arranged in stepped series on the other member and means for moving the pivoted member from 110 the handle opening into the recess of the lever upon opening of the switch.

11. An electric switch comprising a stationary contact member, a second contact member normally under tension to open and 115 movably connected therewith, a slideable catch connected to the first member, and an operating device for the second member, interlocking with a part of the catch for camming thereagainst to render the catch 120 inoperative by and during movement of said device to its inoperative position.

12. An electric switch comprising a handle having a recess, a contact support in the handle recess, a movable contact pivoted 125 within the handle recess, a catch movably supported to engage the movable contact to lock the same closed, a lever pivotally connected to the handle and having connection with the catch to operate the same, 130

and a coiled spring connected to the outer end portion of the lever and to a fixed point offset relative to the pivotal mounting of said lever.

- 5 13. In an electric iron, and in combination therewith, a stationary contact carrying member fixed within the handle of the iron, a number of separate contacts in series on the stationary member, leads connected to 10 the terminal contacts of the series, a movable member working in a recess in the handle, a number of separate contacts in series on the movable member, an operating member recessed to embrace the movable member, a relatively strong spring acting on the 15 movable member and a relatively weak spring acting on the operating member.

14. The combination with a tool handle having a recess therein; of a switch comprising a stationary contact member fixed within said recess, a movable contact member working in said recess, an independently movable operating member recessed to embrace said movable member and having 25 a tendency to occupy a position at which said contact members will be in disconnected relation, and retarded means controlled by said operating member for disconnecting said contact members.

- 30 15. The combination with a tool handle having a recess therein; of a switch com-

prising a stationary contact member fixed within said recess, a movable contact member working in said recess, an operating member recessed to embrace said movable member and having a tendency to occupy a position at which said contact members will be in disconnected relation, and said movable contact member being normally under tension to separate itself from said stationary member which tension is relatively greater than the aforementioned tendency of said operating member.

16. The combination with a tool handle having a recess therein; of a switch comprising a stationary contact member fixed within said recess, a movable contact member working in said recess, an operating member recessed to embrace said movable member and having a tendency to occupy a position at which said contact members will be in disconnected relation, said movable contact member being normally under tension to separate itself from said stationary member which tension is relatively greater than the aforementioned tendency of said operating member, latching means for said movable member, and releasing means for said latching means controlled by said operating member.

CLAUDE WILLIAM DENNY
